DINNER PLATE OR SIMILAR ARTICLE

Michael J. Szymanski, Camillus, N.Y., assignor to Syracuse China Corporation, Syracuse, N.Y.

Filed Apr. 22, 1971, Ser. No. 136,643

Int. Cl. D7—01

U.S. Cl. D44—15

FIG. 1 is a plan view of a dinner plate of conventional configuration showing my new design; and

FIG. 2 is a plan view of a portion of the design shown between the dot-and-dash lines on FIG. 1 to an enlarged scale.

I claim:

The ornamental design for a dinner plate or similar article, as shown and described.
